United States Patent Office.

H. E. FRÖHLICH, OF EASTON, PENNSYLVANIA.

Letters Patent No. 67,524, dated August 6, 1867.

IMPROVEMENT IN THREAD-GUIDE FOR SEWING MACHINE.

The Schedule referred to in these Letters Patent and making part of the same.

TO ALL WHOM IT MAY CONCERN:

Be it known that I, H. E. FRÖHLICH, of Easton, in the county of Northampton; and State of Pennsylvania, have invented a new and useful Improvement in Sewing Machines; and I do hereby declare that the following is a full, clear, and exact description thereof, which will enable those skilled in the art to make and use the same, reference being had to the accompanying drawings, forming part of this specification, in which—

Figures 1, 3, and 4 are side views of my invention.

Figures 2 and 5 are end views of the same.

Similar letters of reference indicate corresponding parts.

This invention relates to certain improvements on the button-hole sewing machine for which Letters Patent were granted to D. W. G. Humphrey on the 7th day of October, 1862, 29th of August, 1865, and October 3d, 1865. Said improvements consist in the use of wire arms, which are laid over the spools for the purpose of holding the thread, and for preventing it from slipping, said arms being secured stationary to the machine.

A, fig. 1, represents one of the two spools which are arranged on the under side of the machine, and around which one of the threads is wound. A portion of the platform of the sewing machine is represented by red lines. B is a wire, one end of which is secured to a metal jaw, C, which is provided with a set-screw, D, by which the wire is secured to the flange around the platform. The wire is bent so as to fit over the spool, and its free end is perforated, for the thread to pass through, as is clearly shown in fig. 1. The thread, by the use of this device, is prevented from falling off the spool, and its tension is increased. E, figs. 2 and 3, is a similar wire, which is also secured to a jaw, C, and provided with a set-screw, D, and with a hole in its free end. It is to be used for the other spool below the platform of the machine, for the same purpose above set forth. A wire, F, which is similarly connected and arranged, is secured to the top of the machine, and applied to the upper spool, also for the purpose of retaining the thread on the spool, and for increasing the tension.

I claim as new, and desire to secure by Letters Patent, as an improved article of manufacture—

The wires B E and F, when arranged substantially as and for the purpose herein shown and described, in combination with the jaws C and set-screw D, all to be applied to the button-hole sewing machine, as set forth.

H. E. FRÖHLICH.
